G. P. CRAGIN

CUFF

Filed Dec. 15, 1922

George P. Cragin Inventor

By *Herb E. Smith*

Attorney

UNITED STATES PATENT OFFICE.

GEORGE P. CRAGIN, OF SPOKANE, WASHINGTON.

CUFF.

Application filed December 15, 1922. Serial No. 607,196.

To all whom it may concern:

Be it known that I, GEORGE P. CRAGIN, a citizen of the United States, residing at Spokane, in Spokane County and State of Washington, have invented certain new and useful Improvements in Cuffs, of which the following is a specification.

The present invention relates to improvements in cuffs of the soft, detachable type, for use with the wrist-band on sleeves of shirts, shirt-waists, &c. The cuffs which are foldable may readily be reversed and thus adapted for extended use, and when so reversed, the cuffs are worn on the opposite sleeves, i. e. the cuff formerly worn on the right sleeve is changed to the left, and vice versa. The cuffs of each pair are made of similar construction and adapted for use of both faces or sides by the utilization of the obverse and reverse sides, and while it is preferable that the reversed cuffs be used as hereinafter indicated, it will be obvious that the wearer may consult his own convenience in the use of the cuffs.

The invention consists essentially in certain novel features of construction and arrangements of the cuffs whereby they are attached to the sleeve and maintained in such manner as to give a straight effect from the elbow to the cuff point, thus enhancing the appearance of the cuff and sleeve, and comfort for the wearer is secured by the efficient manner in which the cuff is retained on the wristband of the sleeve. By the utilization of my invention the cuff is manufactured in such manner as to secure economy in the use of the material required, and means are provided whereby the cuff may with facility be attached and detached, and reversed when desired for extended use.

In the accompanying drawings I have illustrated one complete example of the physical embodiment of my invention and a modification thereof, wherein the parts are combined and arranged according to modes I have thus far devised for the practical application of the principles of my invention.

Figure 1 is a view showing a left hand cuff fashioned according to my invention and attached to the sleeve, showing a corner

of the outer and inner folds turned back to disclose the manner of attachment to the sleeve button.

Figure 2 is a plan view of a cuff according to my invention, before folding. 55

Figure 3 is a plan view of a modified form of the cuff.

Figure 4 is an enlarged, sectional view at line 4—4 of Figure 3.

The cuff as illustrated is of generally rectangular form and is made up of a plurality of plies or layers of material, and stitched as usual around the four edges. In use it is folded along its central longitudinal line or axis to provide an outer fold 1 and an inner fold 2, and each of these folds is provided with a pair of complementary button holes, 3, 3' and 4, 4' for the cuff-button 5 and its shank, the button being used in well known manner. These pairs of button holes, 60 as shown, are located at the approximate longitudinal centers of the folds 1 and 2 near their edges, and the pairs of holes are of course adapted to register when the cuff is folded in position for wear. 75

For the purpose of securing economy in material and consequent saving in cost of manufacture, and to facilitate the operations of attaching and detaching the cuff, I cut away a rear corner 7 of the cuff, and attach 80 thereto a tab 8 having a button hole 9 for connection with the sleeve button 10. The tab is preferably made up of the same material as the cuff, and is inserted in an opening provided therefor at the cut-away corner, between the plies of the cuff, after which the cuff and the encased portion of the tab are stitched together as at 11 in Figure 2. 85 The plies may be evenly separated and the tab inserted between them in proper position with its inner edge approximately in alinement with the inner edge of the cuff, but with the free end of the tab extending beyond the side of the cuff as shown.

Within the fold 2, near its corner opposite to the cut-away corner 7, a complementary button hole 12 is provided to register with the button hole 9 of the tab 8. By means of these holes 9 and 12, and the button 10, the opposite side edges of the inner 100

fold 2 are secured to the wristband, holding the cuff in secure and fixed position on the wristband.

In the operation of attaching the cuff to the sleeve, as indicated in Figure 1, the cuff with its button 5 in place, is slipped over the wristband 13 of the sleeve 14, with the inner fold 2 around the wristband, the placket of which is fastened together by the button 10. The tab 8 is then bent under and outwardly around the meeting portions of the band and the button hole 9 passed over the button 10. The opposite end of the inner fold 2, which is in position for the button hole 12 to register with the button 10, is now secured to the button by means of the hole 12 with the fold lying over the tab.

In actual use the button 10, tab 8, and the inner fold are concealed from view by the outer fold 1, which covers these parts, and the cuff thus presents a neat and attractive appearance. If desired by the wearer the folded cuff may be attached to the sleeve by means of button 10 before the cuff-button 5 is passed through the complementary holes 3, 3', 4, 4' but of course the cuff will be folded before being buttoned on the sleeve regardless of the method used in putting on the cuffs.

For extended use of the cuffs they may be reversed, after removal from the sleeve, by turning the outer fold 1 back over fold 2 whereupon the obverse face becomes the enclosed or interior portion of the cuff while the reverse face becomes the exterior or visible portion of the cuff, thus presenting a fresh appearance for the cuff. When so reversed the cuff previously used on the left hand is worn on the right wrist and the cuff formerly used on the right hand is transferred to the left wrist. In this reversed position of the cuffs the button-hole 12 and tab 8 is the sole means utilized for attaching the cuff to the button 10, said tab being turned inwardly and under around the closed placket of the sleeve at the wristband. Of course convenience and habit of the wearer may be factors in deciding the mode of procedure for attaching and detaching the cuffs, but the foregoing is a description of a facile mode for using the cuffs.

In the form of the invention illustrated in Figures 3 and 4, the outer and inner folds 15 and 16 of the cuff have registering pairs of button holes 17, 17', 18, 18' for the cuff button, and the inner fold 16 is cut away at both corners 19 and 20, for further economy in material and also for the purpose of insuring facility in buttoning the cuff to the wristband of the sleeve.

The comparatively long tab 21, which is provided with the button hole 22 for use with the button 10, is stitched at one end of the cuff, while a shorter tab 23, with

button hole 24 is stitched at the opposite end of the cuff. The inner ends of these tabs are inserted in openings between the plies as 25 and 26 of the cuff and secured by means of the rows of stitching indicated at 11' in Figure 3, and the inner edges of the tabs lie in a parallel plane with the inner edge of the cuff, but offset therefrom the slight width of the stitched portion along the edge of the cuff. The longer tab 21, with its hole 22 beyond the right end of the cuff, is designed to bend around the meeting edges of the placket of the wristband, while the tab 23 is of sufficient length to bring the hole 24 in position to register with the button 10 after the buttonhole 22 has been slipped over said button.

As illustrated in Figure 4 it will be apparent that the buttonhole tabs are firmly secured and held in place by the stitching, as indicated at 11 or 11', to insure durability and protect the cuff from wear and tear in use as well as in laundering.

To apply the folded cuff of Figure 3 to the wristband of the sleeve, with the cuff button in place, the cuff is slipped over the wrist and wristband as usual, and the tab 21 then secured to the sleeve button, after which the tab 23 of the inner fold 16 is secured on the button over the tab 21. To remove this cuff the steps just set forth are reversed, and to reverse the cuff it is folded over backward in the opposite direction, bringing the reverse side or face on the exterior and concealing the used side within the cuff.

It will be noted that the tabs 8 and 21, as in Figures 1 and 3, when passed around the meeting edges of the placket at the wristband, form an effective closure for the band, and these tabs project or extend beyond the end of the cuff a sufficient length for this purpose. The tab 23 of Figure 3, however terminates with its extreme, free edge approximately in alignment with the left end of the cuff in said figure of the drawings, in order that its buttonhole 24 will register with the sleeve button 10.

As thus fashioned and in this manner attached, the cuffs are adapted to assume and maintain a neat appearance for the well groomed or fastidious person, and they insure comfort for the wearer as well as convenience and facility during the process of attachment and detachment to and from the sleeve.

Having thus fully described my invention, what I claim as new and desire to secure by Letters Patent is:

1. A soft reversible cuff foldable longitudinally to form an inner fold and an outer fold each having a pair of complementary cuff-button holes, the inner fold

having a cut-away corner, and a button-hole tab secured at said corner and projecting beyond the straight edge of the cuff.

5 2. A soft reversible cuff adapted to form an inner and outer fold, the inner fold having its corners cut away, longitudinally

extending button hole tabs attached at said corners, and one of said tabs having its free end projecting beyond the complementary straight edge of the cuff. 10

In testimony whereof I affix my signature.

GEORGE P. CRAGIN.
